7 Claims

ABSTRACT OF THE DISCLOSURE

A changeable display device which can be made integral with various items, the items thereupon being provided with a window through which the display is viewed. A rotatable member carrying information to be displayed is moved, via linkages attached to a movable member of the item, so as to change the display each time the item is employed.

BACKGROUND OF THE INVENTION**(1) Field of the invention**

The present invention relates to the display of messages. More specifically, the present invention is directed to items having a changeable indicia display mechanism integral therewith. Accordingly, the general objects of the present invention are to provide novel and improved methods and apparatus of such character.

(2) Description of the prior art

While not limited thereto in its utility, the present invention has been found to be particularly well suited to employment in clip devices for retaining papers. The present invention may also be employed in cigarette lighters, knives and, in the clip embodiment, as a badge which will be clamped onto wearing apparel. Regardless of the field of use, items of the type with which the present invention may be employed, when used to convey information, have previously presented a static display. Thus, in the prior art when it was desired, for example, to employ clamp devices as an advertising medium, the desired message was customarily painted on the device.

As is well known, a moving or changeable display is much more apt to attract attention than a static display. However, as noted above, items available in the prior art could display only a single, nonalterable message or design.

SUMMARY OF THE INVENTION

The present invention overcomes the above briefly discussed disadvantages of the prior art and in so doing provides a novel moving display device. In accordance with the present invention, one component of an item which is to be used for displaying a message is provided with a viewing window. Positioned behind the viewing window is a rotatable member which bears a plurality of spacially displaced indicia which are to be displayed through the window. The rotatable indicia bearing member is provided with projections or holes which are engaged by a lever mechanism mounted internally of the item. The lever mechanism is operated by a projection which is affixed to a movable component of the item which does not have the window therein. Each time the movable component is operated, the projection will engage the lever mechanism which in turn engages the rotatable indicia bearing member thereby causing the display viewed through the window to be changed in stepwise fashion.

BRIEF DESCRIPTION OF THE DRAWING

The present invention may be better understood and its numerous objects and advantages will become apparent

2

to those skilled in the art by reference to the accompanying drawing wherein like reference numerals refer to like elements in the several figures and in which:

FIG. 1 is an isometric view of a first embodiment of a clamp device employing the present invention.

FIG. 2 is a side view, partly in section, of the embodiment of FIG. 1 taken along line 2—2 of FIG. 1.

FIG. 3 is a view of the message-changing mechanism of the embodiment of FIG. 1, the view in FIG. 3 being taken along line 3—3 of FIG. 2.

DESCRIPTION OF THE PREFERRED EMBODIMENT

With reference now to FIG. 1, a clamp or clip device employing the present invention is shown generally at 10. As is common in the art, clamp 10 comprises oppositely disposed jaw members 12 and 14. The jaw member 12, which will function as the front of the clamp, is provided with a viewing window 16. Window 16, in the usual instance, will comprise a rectangular slot in jaw member 12; a transparent plastic element commensurate in size with the slot being snapped or press-fit therein.

Jaw members 12 and 14 are normally maintained in the closed position shown in FIG. 1 by means of a spring 18. Spring 18 comprises a strip of spring steel which, as may best be seen from FIG. 2, extends between jaw members 12 and 14 and is formed into a substantially C-shape. The clamp is opened by pressing members 12 and 14 together at the end opposite to the normally closed jaws thereby compressing spring 18. Through the action of spring 18, release of pressure at the top of members 12 and 14 permits the clamp to resume its closed position. Jaw members 12 and 14, when opening and closing, pivot about a pair of pivots 19, only one of which is shown in FIG. 1, which pass through inwardly extending arms at each side of each of jaw members 12 and 14 intermediate the length of the jaw members.

In the embodiment shown in FIG. 1, the indicia bearing member comprises a rotatable disc 30 (see FIGS. 2 and 3) which bears a plurality of messages or indicia on its front face. Disc 30 is provided with eccentrically positioned cutouts 31 which, as will be described in detail below, are engaged by the message-changing mechanism. Disc 30 is held in position adjacent the rear surface of jaw member 12 and with the indicia thereon alignable with window 16 by means of a plate 20. Plate 20 has a short projection or dimple therein which engages a depression at the center rear of disc 30 and disc 30 is provided with a dimple, not shown, which provides a bearing surface which rests against the rear of clamp member 12, the disc member rotating on this bearing surface.

With reference now to FIG. 2, it may be seen that plate 20 is provided with a semicircular, inwardly extending projection 22. The rear or other clamp member 14 has, suitably affixed thereto, an inwardly extending projection 24 which is pivotably connected to semicircular projection 22 intermediate its length by a rivet or other suitable means 26. The free end of forwardly extending projection 24, i.e. the end adjacent the rear surface of clamp member 12, is provided with a slot which engages a lever arm indicated generally at 28. As may best be seen from FIG. 3, lever arm 28 is pivotably attached to the rear surface of plate 20. The point of attachment of lever arm 28 is adjacent one side of plate 20 and is so located that the lever arm will cross the axis of rotation of disc 30 intermediate its stroke.

Lever arm 28 is provided, at its free end, with a transverse extension or ratchet arm 29 which passes through a curved slot 34 in plate 20 and, in the manner to be explained below, engages the side of the cutouts 31 in rotatable disc 30. As should now be obvious, opening of

clamp 10 by forcing jaw members 12 and 14 together at their top or normally open ends will cause projection 24 to rotate about pivot point 26. Rotation of the free end of projection 24, since lever arm 28 is engaged in the slot therein, causes the lever arm to turn about its pivot point and arm 29 will thus travel in curved slot 34. Since arm 29 will engage the side of one of cutouts 31 in disc 30, movement of the lever arm 28 resulting from opening of the clamp will cause the disc 30 to turn and the display viewed through window 16 to change.

Referring again to FIGS. 2 and 3, it may be seen that plate 20 is provided with a forwardly extending member, indicated generally at 32, which functions as a pawl. Pawl member 32 is formed by providing a cut in plate 20 adjacent curved slot 34 and the end 33 of pawl 32 is turned outwardly whereby it will engage the sides of cutouts 31 in disc 30.

In operation, each time the clamp 10 is opened, the lever arm 28 will be moved from the position shown in FIG. 3 to the bottom of slot 34. In so moving, the lever arm will engage one of the cutouts 31 in disc 30 and thus cause the display viewed through window 16 to change. When the opening force on clamp 10 is released, lever arm 28 will return to its initial position and projection 29 will drop into another one of cutouts 31 in disc 30. As the lever arm returns, ratchet arm 29 will ride up over the rear surface of disc 30, disc 30 being held against movement in the clockwise direction, as viewed in FIG. 3, by engagement of the end 33 of pawl 32 with the side of one of cutouts 31.

While a preferred embodiment has been shown and described, various modifications and substitutions may be made thereto without departing from the spirit and scope of the present invention. Thus, for example, the indicia bearing rotatable member may be in the form of a cylinder rather than a disc and the message-changing means may comprise a ratchet and pawl mechanism with projection 24 functioning as a reciprocating lever which engages a ratchet wheel on the message cylinder. Also, the member which carries the reciprocating projection may, for example, be the base of a knife blade or the cover of a cigarette lighter. Accordingly, it is to be understood that the present invention has been described by way of illustration and not limitation.

What is claimed is:

1. A display device comprising:
a rotatable member, said member having a plurality of spacially displaced indicia on the front surface thereof, said member further being provided with a plurality of equally spaced drive surfaces;
a reciprocating actuator member;
a pivotal lever engaged by one end of said actuator member, said lever being oriented substantially transversely of said actuator member and being engaged thereby adjacent a first end thereof; and

a projection extending from the other end of said lever, said projection being integral with said lever and being oriented substantially parallel to said actuator member, said projection releasably engaging said rotatable member drive surfaces for imparting movement to said member in one direction, said projection and said point of engagement of said lever by said actuator member both being on the same side of the point about which said lever pivots.

2. The device of claim 1 further comprising:
pawl means for restraining said rotatable member from movement in the opposite direction.

3. The device of claim 2 wherein said rotatable member comprises:
a disc having a plurality of apertures therein, said apertures defining at one side thereof said drive surfaces.

4. The device of claim 1 further comprising:
support means on which said rotatable member rotates, said support means being provided with a viewing window aligned with said indicia, one indicia being viewed through said window at a time.

5. The device of claim 4 wherein said actuator member comprises:
an arm having a first end which engages said lever;
means pivotally supporting said arm from said support means intermediate its length whereby the end of said arm which engages said lever is constrained to reciprocating motion; and
clamp means rigidly connected to the second end of said arm, said clamp means being commensurate in size with said rotatable member supporting means and cooperating therewith to define a display device wherein the rotatable indicia bearing member is actuated by relative movement between said clamp means and rotatable member supporting means.

6. The device of claim 5 further comprising:
pawl means for restraining said rotatable member from movement in the opposite direction.

7. The device of claim 6 wherein said rotatable member comprises:
a disc having a plurality of apertures therein, a wall of each of said apertures defining a drive surface and being serially engaged by said lever projection during movement of said lever in a first direction, a wall of each of said apertures being engaged by said pawl during return of said lever in a second direction.
